WATER DRIVEN FOUNTAIN BRUSH

William Fleming, Los Angeles, Calif.

Application December 30, 1952, Serial No. 328,675

3 Claims. (Cl. 15—29)

1

This invention relates to fountain brushes useful in different sizes for washing various types of washable objects from dishes to automobiles, and more particularly to a water driven fountain brush having detergent dispensing means associated therewith.

It is among the objects of the invention to provide an improved fountain brush which is rotatably driven by the water supplied thereto; which has detergent dispensing means associated therewith for adding detergent material to the water supplied to the brush; which is so constructed and arranged that the brush is locked against rotation and the flow of water is reduced when the water supply is turned on and the brush is not in use; which can be easily attached to available water supply conduits, such as sink faucets and garden hoses; and which is simple and durable in construction, economical to manufacture, effective in use, and neat and attractive in appearance.

Other objects and advantages will become apparent from a consideration of the following description and the appended claims in conjunction with the accompanying drawing wherein:

Figure 1 is a side elevational view of a water driven fountain brush illustrative of the invention;

Figure 2 is a top plan view of the brush illustrated in Figure 1;

Figure 3 is a bottom plan view of the brush;

Figure 4 is a cross sectional view on an enlarged scale on the line 4—4 of Figure 2;

Figure 5 is a cross sectional view on a reduced scale on the line 5—5 of Figure 4;

Figure 6 is a cross sectional view on a reduced scale on the line 6—6 of Figure 4;

Figure 7 is a cross sectional view on a reduced scale on the line 7—7 of Figure 4; and

Figure 8 is a fragmentary cross sectional view on the line 8—8 of Figure 4.

With continued reference to the drawing, the brush comprises a housing, generally indicated at 10, including an annular and preferably cylindrical side wall 11, a top wall 12, a bottom wall 13 spaced from the top wall 12, and a partition wall 14 disposed between the top and bottom walls of the housing and dividing the interior of the housing into an impeller chamber 15 and a detergent chamber 16.

The transverse walls 12, 13 and 14 are all disposed substantially perpendicular to the longitudinal center line or axis of the cylindrical side wall 11 of the housing and the top wall is removably mounted on the housing by having

2

thereon a marginal flange 17 of cylindrical shape which receives the corresponding end of the housing side wall. The bottom wall 13 is marginally secured in an annular groove provided in the side wall by beading a portion of the side wall outwardly to provide a groove at the inner side and an annular bead or rib 18 at the outer side of the housing and the partition wall 14 is similarly secured in the housing by having its edge engaged in an annular groove in the housing formed by an annular bead formation 19 surrounding the housing.

An impeller 20 in the form of a star wheel is disposed in the impeller chamber 15 in the housing with the outer ends of its vanes substantially in engagement with the inner surface of the housing side wall 11 and this impeller has a bore 21 of noncircular and preferably polygonal cross sectional shape extending coaxially therethrough.

The bottom wall 13 is provided with a central aperture 22 and the partition wall 14 is provided with a central aperture 23, the apertures 22 and 23 being disposed coaxially of the bore 21 in the impeller and an axle, generally indicated at 24, has an intermediate portion 25 of noncircular or polygonal cross sectional shape slidably received in the bore 21 of the impeller and end portions 26 and 27 of circular cross sectional shape and of reduced diameter extending longitudinally

from the respectively opposite ends of the intermediate portion 25 coaxially of the intermediate portion and through the apertures 22 and 23 respectively. The bottom wall 13 is provided with a socket formation 28 surrounding the aperture 22 in the bottom wall and opening to the impeller chamber 15, this socket being shaped to receive the adjacent end of the intermediate portion 25 of the axle 24 and hold the axle and the impeller 20 against rotation whenever the axle is engaged in the socket.

A brush, generally indicated at 30, is concentrically mounted on the outer end of the axle extension 26 and is spaced from the outer side of the bottom wall 13 and substantially parallel to the bottom wall. This brush comprises a hub 31 in the form of a circular disc having a central aperture receiving a screw 32 which secures the disc to the outer end of the axle extension 26, and hook formations 33 curved inwardly from the peripheral edge of the disc at substantially equal angular intervals around the disc, and a twisted wire and bristle structure 34 having somewhat the shape of a Maltese cross secured to the hub 31 concentrically of the hub

3

by having its inner angles secured one in each of the hooks 33.

The axle extension 27 disposed in the detergent chamber 16 is provided with a longitudinally extending closed slot 35 and an agitator 36 in the form of a longitudinally twisted strip of sheet material extends through the slot 35 to an extent such that the extension 27 is disposed substantially at the mid-length location of the strip. The slot 35 is longer than the width of the agitator strip, so that the axle 25 has a limited freedom of longitudinal movement to permit the end of the intermediate portion 25 of the axle adjacent the bottom wall 13 of the housing to move into and out of the socket 28 in the bottom wall.

A split clamp band 40 surrounds the housing side wall 11 between the annular ribs 18 and 19 and has its ends constituting apertured lugs projecting outwardly from the housing side wall and secured together by a clamp screw 41 which firmly binds the clamp band 40 around the housing side wall. A tubular conduit 42 has one end secured to the band 40 and extending through an aperture in the side wall 11 of the housing in a direction to direct a jet of water into the impeller chamber 15 in the housing substantially tangentially of the impeller 20. The conduit 42 is provided with bends 43 and 44 spaced apart intermediate the length thereof, so that while the end portion of this conduit adjacent the housing extends substantially tangentially from the housing intermediate the height of the impeller chamber 15, the opposite end portion of the conduit extends substantially radially from the housing above the impeller chamber. An elongated brace 45 of either solid or tubular construction has substantially the same length and shape as the conduit 42 and has one end portion extending along the end portion of the conduit 42 remote from the housing, and its other end secured to the clamp band 40 at a location spaced angularly around the housing from the corresponding end of the conduit 42. An elongated tubular handle 48 receives the end portion of the conduit 42 and the brace 45 remote from the housing, the conduit and the brace providing a rigid connection between the handle and the housing. A hose fitting 50 is secured on the end of the conduit 42 remote from the housing for connection of one end of a flexible hose to the brush. This flexible hose may be a garden hose, if desired, or may be a short length of flexible tubing, one end of which is connected to the brush, and the other end of which is connected to a water supply conduit, such as a sink faucet, to equip the brush for washing dishes in a sink.

The partition wall 14 is provided near its edge with apertures 51 and 52 of which the aperture 51 is disposed near the end of the conduit 42 communicating with the impeller chamber 15 and the aperture 52 is disposed at the opposite side of the axle 25 from the aperture 51, so that water will flow from the impeller chamber through the aperture 51 into the detergent chamber 16 and will flow from the detergent chamber through the aperture 52 back into the impeller chamber.

It is to be understood that before the brush is put to use, the cover constituted by the top wall 12 and flange 17 will be removed and a supply of detergent placed in the detergent chamber 16 and the cover then replaced.

The bottom wall 13 is provided with small, closely spaced apertures 54 distributed substan-

4

tially uniformly over the area thereof and through which water passes from the impeller chamber 15 to the brush 30.

When the water is turned on to the brush and the brush is not being used, the water flowing through the conduit 42 into the impeller chamber 15 will act on the blades or vanes of the impeller tending to rotate the impeller and, at the same time, the water flowing through the apertures 54 in the bottom wall 13 against the adjacent side of the brush 30 will urge the brush away from the bottom wall and the force exerted by the water on the brush will seat the end of the intermediate portion 25 of the axle 24 in the socket 28 and hold the impeller and the brush against rotation. When the impeller is thus locked against rotation, water can flow to the brush only through those apertures in the bottom wall disposed in the space between rotor vanes disposed at respectively opposite sides of the end of the conduit 42 extending through the side wall 11 of the housing and the flow of water, when the impeller is thus locked against rotation, is only a fraction of the flow of water through the brush when the impeller is free to rotate. When the brush is pressed against the surface of an object to be washed, this pressure moves the axle 24 longitudinally, so that the intermediate portion 25 of the axle is moved out of engagement with the socket 28, thus freeing the rotor 20 to rotate and drive the brush 30. While the rotor is rotating, all of the apertures in the bottom wall 13 of the housing are rendered effective for the passage of water from the interior of the housing to the brush 30 and the flow of water is thus greatly increased when the brush is in use. When the brush is in use with the increased flow of water described above, some of the water will flow through the apertures 51 and 52 into and out of the detergent chamber 16 adding a regulated amount of the detergent to the water flowing to the brush 30, so that detergent is applied as the object is scrubbed by the brush.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

55 What is claimed is:

1. A fountain brush comprising a housing having an annular side wall, substantially parallel top and bottom walls and a partition wall disposed between said top and bottom walls dividing the interior of said housing into an impeller chamber and a detergent chamber, an impeller in said impeller chamber having a bore of polygonal cross sectional shape extending coaxially therethrough, said bottom wall and said partition wall each having a centrally disposed aperture therein concentric with the bore in said impeller and said bottom wall having a socket formation on noncircular cross sectional shape surrounding the aperture therein and opening into said impeller chamber, an axle having an intermediate portion of noncircular cross sectional shape slidably received in the bore of said impeller and coaxial end extensions of reduced diameter extending respectively through the 70 apertures in said bottom and partition walls, a

brush coaxially mounted on said axle at a location spaced from the outer side of said bottom wall, said axle having a longitudinally extending closed slot in the portion thereof within said detergent chamber, an agitator element disposed in said detergent chamber extending through said slot and having a portion in said slot of a width less than the length of said slot to provide a limited freedom of longitudinal movement for said axle, a tubular conduit of rigid construction secured at one end to said housing and extending substantially radially from said annular side wall with a hose connection formation on its other end, and a handle on said conduit, said conduit being effective to direct a jet of water into said impeller chamber substantially tangential to said impeller, said partition plate having spaced apart apertures therein for the passage of water from said impeller chamber into said detergent chamber and from said detergent chamber back into said impeller chamber and said bottom wall having closely spaced apertures therein for the passage of water from said impeller chamber to said brush to supply water to the brush and urge the brush away from said bottom wall to seat the end of the intermediate portion of said axle adjacent said bottom wall in said socket formation and restrain said impeller from rotation, said axle being moved out of said socket to free said impeller for rotation by pressure of said brush against the surface of an article being washed.

2. A water driven fountain brush comprising a housing enclosing an impeller chamber and having a perforate end wall provided with a centrally located socket, an impeller rotatable in said housing and having a coaxial bore in registry with said socket, an axle extending through said bore, said socket and said end wall and having a limited freedom of longitudinal movement for movement into and out of engagement

with said socket, said impeller being drivingly connected to said axle and said axle being held against rotation when engaged in said socket, a brush coaxially secured to said axle at a location spaced from the outer side of said end wall and effective when subjected to pressure on its side remote from said end wall to move said axle out of engagement with said socket and free said impeller and said axle for rotation, and a conduit connected at one end to said housing in position to direct a jet of water into said impeller chamber substantially tangentially of said impeller, the water flowing from said impeller chamber through said perforate end wall to said brush and exerting a force on said brush tending to engage said axle in said socket.

3. A water driven fountain brush comprising a housing enclosing an impeller chamber and having a perforate end wall, an impeller rotatable in said housing and having a coaxial bore, an axle extending through said bore and said end wall and drivingly connected to said impeller, a brush coaxially secured to said axle at a location spaced from the outer side of said end wall, a conduit connected at one end to said housing in position to direct a jet of water into said impeller chamber substantially tangentially of said impeller, and means carried by said end wall and engageable with said axle to lock said axle and said impeller against rotation when said brush is subject at its side adjacent said end wall to the pressure of water flowing from said impeller chamber through said perforate end wall and free of pressure on its side remote from said end wall and to release said axle for rotation of said axle and said impeller when said brush is subjected to pressure at its side remote from said end wall.
